UNITED STATES PATENT OFFICE.

CHARLES S. WALTOWER, OF ENSLEY, ALABAMA.

DESIGN FOR A PACKAGE-TIE.

46,849.

Specification for Design.

Patented Jan. 5, 1915.

Application filed October 6, 1914. Serial No. 865,385. Term of patent 3½ years.

To all whom it may concern:

Be it known that I, CHARLES S. WALTOWER, a citizen of the United States, residing at Ensley, in the county of Jefferson and State of Alabama, have invented a new, original, and ornamental Design for a Package-Tie, of which the following is a specification, reference being had to the accompanying drawing, forming part thereof.

The figure is a perspective view, showing my new design, for a package tie.

I claim:

The ornamental design for a package tie, as shown.

CHARLES S. WALTOWER.
